US0D1060276S

(12) **United States Design Patent** (10) **Patent No.:** **US D1,060,276 S**
(45) **Date of Patent:** ** *Feb. 4, 2025

(54) **CONTROL DEVICE**

(71) Applicant: **Lutron Technology Company LLC**,
Coopersburg, PA (US)

(72) Inventors: **Gregory Altonen**, Easton, PA (US);
Susan Hakkarainen, Doylestown, PA
(US); **Jason C. Killo**, Emmaus, PA
(US); **Brad Michael Kreschollek**,
Bethlehem, PA (US); **Matthew Philip
McDonald**, Phoenixville, PA (US)

(73) Assignee: **Lutron Technology Company LLC**,
Coopersburg, PA (US)

(*) Notice: This patent is subject to a terminal disclaimer.

(**) Term: **15 Years**

(21) Appl. No.: **29/911,688**

(22) Filed: **Sep. 7, 2023**

CLAIM

The ornamental design for a control device as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines illustrate structure or features which form no part of the claimed design.
